GUN SIGHT RIB

Harry F. Moneymaker, Omaha, Nebr.

Application August 24, 1948, Serial No. 148,268

Term of patent 7 years

(Cl. D30—1)

To all whom it may concern:

Be it known that I, Harry F. Moneymaker, a citizen of the United States of America, residing at Omaha, in the county of Douglas and State of Nebraska, have invented a new, original, and ornamental Design for a Gun Sight Rib, of which the following is a specification, reference being had to the accompanying drawing, forming part thereof.

Figure 1 is a plan view of a gun sight rib, showing my new design.

Fig. 2 is an enlarged plan view of a section of the gun rib.

Fig. 3 is a sectional view taken on line 3—3 of Fig. 2.

The dotted lines shown in Fig. 1 of the drawing, are for illustrative purposes only.

I claim:

The ornamental design for a gun sight rib, as shown and described.

HARRY F. MONEYMAKER.
